UNITED STATES PATENT OFFICE.

LEWIS E. WATERMAN, OF ROCKFORD, ILLINOIS, ASSIGNOR TO EMERSON MANUFACTURING COMPANY OF ROCKFORD, ILLINOIS, A CORPORATION OF ILLINOIS.

CULTIVATOR.

SPECIFICATION forming part of Letters Patent No. 761,784, dated June 7, 1904.

Application filed March 30, 1904. Serial No. 200,807. (No model.)

To all whom it may concern:

Be it known that I, LEWIS E. WATERMAN, a citizen of the United States, residing at Rockford, in the county of Winnebago and State of Illinois, have invented certain new and useful Improvements in Cultivators, of which the following is a specification.

The object of this invention is to regulate the working depth of the shovels.

10 In the accompanying drawings, Figure 1 is a side elevation of a cultivator embodying my invention. Fig. 2 is a perspective view of so much of a cultivator as is necessary to show the application of my improvements.

15 The cultivator herein shown in the main is the same as patented to me of April 28, 1903, No. 726,596, so that a detailed description is not deemed necessary.

20 The frame 1 is supported upon wheels 2, and drag-bars 3 have a pivotal connection with the main frame at their forward ends. Upon the axle 4 is mounted two mast-arms 5, one for each drag-bar, and to the free end of each of which is pivotally connected a mast 6, having 25 its lower end pivotally connected to a drag-bar 3. The brace-rods 7 connect the upper portions of the mast-arms 5 with the axle 4. To the lower end of each of the mast-arms and in rear of the axle is pivoted a link 8, having 30 its front end in hook form, to which is connected a spring 9, the other end of the spring being connected to the main frame. The rear end of this link is in the form of a toothed segment, as shown at 10. To the center of 35 the toothed segment is pivoted a lever 11, supporting a cam 12. This lever also sup-

ports a spring-actuated thumb-lever 13, having its lower end adapted to enter the notches of the toothed segment. The cam 12 is located just back of the mast-arm 5 and in contact therewith. By means of this arrangement the mast-arm 5 can be adjusted forward, which will move the drag-bar and regulate the depth at which the shovels will work.

I claim as my invention—

1. In a cultivator, the combination of a main frame, a drag-bar pivotally supported thereby, a mast-arm pivotally supported at one end by the main frame, a connection between the mast-arm and drag-bar, a link having a pivotal connection with the mast-arm and a spring connection with the main frame, a cam pivotally supported by the link and made adjustable in connection therewith and bearing against the mast-arm.

2. In a cultivator, the combination of a main frame, a drag-bar pivotally supported thereby, a mast-arm pivotally supported at one end by the main frame, a connection between the mast-arm and drag-bar, a link having a pivotal connection with the mast-arm and a spring connection with the main frame, the link formed with a toothed segment, a lever having a pivotal connection with the link and provided with a dog for engagement with the toothed segment, and a cam supported by the link and bearing against the mast-arm.

LEWIS E. WATERMAN.
